UNITED STATES PATENT OFFICE.

CLIFTON D. PETTIS, OF MAHWAH, NEW JERSEY.

METHOD OF CASTING BRAKE-SHOES.

1,104,928.

Specification of Letters Patent. Patented July 28, 1914.

Application filed October 6, 1913. Serial No. 793,789.

To all whom it may concern:

Be it known that I, CLIFTON D. PETTIS, a citizen of the United States, residing at Mahwah, county of Bergen, and State of New Jersey, have invented certain new and useful Improvements in Methods of Casting Brake-Shoes, of which I do declare the following to be a full, clear, and exact description, reference being had to the accompanying drawings, forming a part of this specification.

The present invention has relation more particularly to the manufacture of that class of brake shoes commonly known as reinforced brake shoes, in which the cast metal which forms the major portion of the body of the shoe is reinforced or strengthened by a pan-shaped back of ductile metal. Types of brake shoes to the manufacture of which my invention relates more particularly are shown in Letters Patent No. 1,065,717 and No. 1,065,719, granted to me June 24, 1913.

In the manufacture of reinforced brake shoes in which the cast metal forming the body of the shoe is reinforced by a surrounding pan-shaped back or shell, it is highly desirable to preserve a large portion of the body of the cast iron unchilled, particularly in parts adjacent the side walls and the attaching lugs of the shoe, and this is true whether the shoe be provided with chilled portions or not. In cast iron brake shoes it is sometimes desired to chill the end portions of the shoes about their wearing face, and again it is sometimes desired that the wearing face shall be free from chill. It is highly desirable to employ in the manufacture of cast metal brake shoes, metal molds, but one objection incident to the use of such molds is that they chill those portions of the cast metal that come in contact therewith; and even where pan-shaped backs or shells are set within such metal molds, the portions of the molds in contact with the outer face of the pans or shells will impart a chill to the cast metal at such points.

My present invention contemplates the manufacture of a reinforced cast metal brake shoe in such manner that a large part of the cast body of the shoe shall be left unchilled, particularly in the area between the back portion of the shoe and the wearing face, or if the wearing face be chilled, then between the back part and that portion of the shoe

that is not affected by the chilling of the 55 wearing face.

It is also highly desirable in the manufacture of reinforced brake shoes that the portions of the cast metal body of the shoe adjacent the attaching lugs shall be left unchilled, since greater strength is thus given to such points of the shoe as are subjected to the severest strains. In carrying out my invention, I suspend the pan or shell of thin sheet metal into which the cast iron to form 60 the body of the shoe will be poured between the mold sections in such manner that the sides, and preferably also the ends, and the back portions of the shoe adjacent the attaching lugs shall be exposed to the air, the 70 effect of such exposure being to prevent chilling of the metal at such points.

In applications for Letters Patent Serial No. 764,825 and 764,826, filed by me in the Patent Office May 1, 1913, I have shown 75 casting apparatus by means of which the invention constituting the subject matter of the present application may be practised, and in order to enable my present invention to be more readily understood, the apparatus illustrated in my said application Serial No. 764,826 is hereinafter illustrated and described.

Figure 1 is a view in side elevation of an apparatus adapted for the practice of my 85 present invention. Fig. 2 is a plan view thereof. Fig. 3 is a view in front elevation. Fig. 4 is a perspective view of a pan-shaped reinforcing shell adapted for use in the practice of my invention. Fig. 5 is a cross section on line 5—5 of Fig. 1. Fig. 6 is a section on line 6—6 of Fig. 2. Fig. 7 is a plan view of a mold section adapted for use in the practise of my invention. Fig. 8 is a cross section showing the construction of the 90 lower mold section illustrated in Fig. 7.

As before stated, the present invention is particularly adapted for casting brake shoes of the type in which the body of the shoe is reinforced by a pan-shaped back or shell of 100 ductile metal. One form of such shoe is shown in Patent No. 1,065,719, granted to me June 24, 1913, and in Figs. 4 to 7 inclusive of the drawings herewith, a shoe of this form is illustrated. As shown, the shoe comprises a body portion A (indicated by the dotted lines in Fig. 4) which is formed of cast metal, together with a reinforced pan-

shaped shell B formed of thin ductile metal (preferably about 1/32 of an inch thick), and united to the body in the casting operation. Within the shell B is shown a reinforcing back B' of thicker metal. The shell is also provided with center and end lugs C and D, which are formed of malleable or ductile metal and which are provided respectively with projections e and d that extend through the back of the shell B and through the reinforcement B' and interlock with these parts to unite the lugs and the reinforcement B' to the shell. As shown, the pan-shaped shell and reinforcement B' are also provided with pouring openings b and in the form shown in Figs. 4 and 6, the end walls of the shell are provided with depending tongues b'.

The lower or body portion of my casting apparatus, in the form shown, consists of a metal block or casting, the upper curved face of which is provided with a long recess or cavity 11, corresponding in length and width to the body of the brake shoe and within which the ductile metal pan or shell is placed in readiness for the casting operation. The depending lugs b', shown in Figs. 4 and 8, will rest upon the bottom of the cavity 11 so that the edges of the pan-shaped back which fit snugly within the cavity are held above the lower surface thereof, and, when the shoe is formed, its face portion projects beyond the edges of the shell. It is sometimes desirable to avoid the chilling of the wearing face of the body of the shoe and the metal adjacent thereto, either in whole or in part, and when this is to be accomplished, the lower mold section 10 will be chambered to receive a body of refractory material 11^a (see Figs. 7 and 8), in the upper surface of which the cavity 11 for molding the lower portion of the body of the shoe will be formed. This body of refractory material may extend throughout the whole length of the cavity of the lower mold section 10 or throughout parts thereof only, according as it is desired to leave a greater or less extent of the wearing face of the shoe unchilled.

Above the body portion 10 of the apparatus are mounted the upper portions or sections 15 and 16 which are arranged to engage the upper part of the shell B and hold it securely in position during the casting operation. For this purpose, these upper sections are provided with recesses 17 of approximately the same width as the shell and within which recesses the upper portion of the shell extends when the sections 15 and 16 are in position above the lower sections 10. The central portions of the upper sections 15 and 16 are provided with cutaway spaces 18 to clear the center lug C of the shell, and the end portions of the upper sections are also cut away, as indicated at 18', to clear

the end lugs D. The cutaway spaces at the center and ends of the upper sections are of such width as to expose a considerable portion of the back of the shell at such points to the air, thereby avoiding the chilling of the cast metal adjacent the attaching lugs of the shoe. Pouring holes 19 are formed in the abutting faces of the sections 15 and 16 and which are adapted to aline with the holes b of the shell B.

At one end of the lower or body portion 10 is provided a pair of upright posts 20, the upper reduced portions of which pass through openings formed in the adjacent ends of the upper sections 15 and 16, so that the posts form pivots about which the sections 15 and 16 may be laterally swung. The upper ends of the posts are provided with nuts 21 and a series of washers 22 interposed between the ends and the upper faces of the sections 15 and 16. At its opposite or front end, the lower or body portion 10 of the apparatus is provided with a standard 25 which is connected thereto by bolts or studs 26. These bolts or studs extend through laterally projecting ears 28 in the lower portion of the standard 25 and are provided with nuts 27 and a series of washers 29 interposed between the ends and the ears 28. At its upper end the standard 25 is provided with laterally projecting arms 30, preferably having slightly upturned ends, and the sections 15 and 16 are provided with forwardly projecting arms or end portions 32 which extend under the arms 30 and engage the lower faces thereof to thereby hold the upper sections 15 and 16 of the apparatus securely in position. The forwardly projecting arms 32 of the sections 15 and 16, as they are swung inwardly to the position shown in the drawings, abut against the vertical portions 31 of the standard 25. The arms or end portions 32 are preferably provided with handles for convenient manipulation.

By reference more particularly to Figs. 1 and 5 of the drawings, it will be seen that the sections 15 and 16 are arranged at a distance above, or spaced away from, the upper part of the lower portion or body 10 of the apparatus, and one object of the present invention is to provide a simple and effective means whereby adjustment of the upper portion or sections 15 and 16 of the apparatus with respect to the lower portion 10 may be effected in order to vary the thickness or vertical dimension of the brake shoe to be formed. It will be understood, of course, that when the pan-shaped shell B is in position within the cavity 11 of the lower or body portion 10 of the apparatus, the walls of the shell will serve to retain the molten metal and form, in effect, a part of the mold. That is to say, the mold is formed by the lower body portion 10 and

the shell B, the upper sections 15 and 16 merely serving to securely hold the shell in position during the casting operation. When the washers 22 at the rear end and the washers 29 at the front end of the apparatus are in the position shown, the sections 15 and 16 will rest upon the shoulders 20^a of the posts 20, and these sections will then be in proper relative position with respect to the lower portion 10 to form a comparatively thin brake shoe. If, however, it is desired to form a thicker brake shoe, one or more of the washers 22 will be transferred from a position above the sections 15 and 16 to a position between such sections and the shoulders 20^a of the posts 20, and similarly, one or more of the washers 29 will be transferred from a position above the laterally projecting portions 28 of the upright 25 to a position on the studs 26 between the laterally projecting portions 28 and the lower portion 10. This transposition of the washers serves to raise the sections 15 and 16 to a greater extent from the lower portion 10 of the apparatus, so that a brake shoe of greater thickness can be cast,—it being understood, of course, that in casting such thicker brake shoe, a wider shell or one having longer lugs or tongues b' will be employed, so that the sections 15 and 16 will close snugly over the top of the shell.

In using my improved apparatus, the sections 15 and 16 will be swung outwardly and a shell B will be placed within the cavity 11 of the lower portion 10, after which the sections 15 and 16 will be swung to closed position, as shown in Fig. 1 of the drawing. It will be understood, of course, that the end lugs and center lug will be attached to the shell before it is placed in the mold. When the shell is thus held between the lower portion 10 and the upper sections 15 and 16, the molten metal or other material from which the body of the shoe is formed will be poured through the holes 19 until the cavity 11 and the shell have been filled, and as the metal is thus poured into the shell, it unites with the shell, so that the latter affords a most effective reinforcement or armor for the shoe.

From the foregoing description it will be seen that inasmuch as the pan-shaped back or shell D is formed of very thin ductile metal, which heats up rapidly when the molten metal is poured into it, those parts of the side and end walls and portions of the back adjacent the attaching lugs, which are not in contact with the mold sections, will have little or no tendency to chill the body of the shoe at such point and this, as has been before stated, is a most desirable feature.

In practice, the precise details of my invention above set out may be varied without departure from the scope of the invention

and features of the invention may be employed without its adoption as an entirety.

Having thus described my invention, what I claim as new, and desire to secure by Letters Patent, is:—

1. The method of forming a reinforced brake shoe that consists in holding against a mold the open side of a metal pan or shell formed of thin ductile metal and having a back and side walls, the side walls being exposed to the air, and pouring molten cast iron into said shell to unite therewith and form the body of the shoe.

2. The method of forming a reinforced brake shoe that consists in holding against a mold the open side of a metal pan or shell formed of thin ductile metal and having back, side and end walls exposed to the air, and pouring molten cast iron into said shell to unite therewith and form the body of the shoe.

3. The method of forming a reinforced brake shoe which consists in holding above the cavity of a mold the open side of a metal pan or shell formed of thin ductile metal and having a back, side and end walls, the side and end walls being exposed to the air, and pouring molten cast iron into said shell and into the cavity of the mold beneath it to form the body of the shoe.

4. The method of casting a brake shoe that consists in placing a metallic shell formed of thin ductile metal and having a back, side and end walls and an open side between a lower mold section and an upper shell-holding means, said shell spanning the space between said mold section and said shell-holding means, and thereafter casting molten iron to form the body of the shoe within said shell, the latter being united to the body of the shoe in the casting operation to reinforce the same and the body projecting through the open side of the shell.

5. The method of casting a brake shoe that consists in placing a shell having a back, side and end walls and open opposite said back between a lower mold section and an upper shell holding means, the body of the shell being held with its open side at a distance from the bottom of the cavity of said mold section and said shell spanning the space between said mold section and said shell-holding means, and thereafter pouring cast metal through the back of said shell to form the body of the shoe, said cast metal uniting with said shell to reinforce the same.

6. The method of forming a reinforced brake shoe that consists in holding against a mold a metal pan or shell formed of thin ductile metal and forming an outline to the back and sides of the finished body of the shoe and being open opposite the back, the end portions of the back of said shell adjacent the attaching lugs being exposed to

the air, and pouring molten iron into said shell to unite therewith and form the body of the shoe.

7. The method of forming a reinforced 5 brake shoe that consists in holding against the mold a metal pan or shell formed of thin ductile metal and having center and end lugs at its back and having a back and side and end walls conforming in shape to the 10 outline of the body of the shoe, said center

and end portions of the pan or shell adjacent said attaching lugs being exposed to the air, and pouring molten iron into said shell to unite therewith and form the body of the shoe.

CLIFTON D. PETTIS.
